SHEET GUIDE FOR PLATEN PRESSES

Cecil P. Kuever, Washington, D. C.

Application October 6, 1947, Serial No. 778,101

1 Claim. (Cl. 101—413)

1

This invention relates to automatic job platen presses and more particularly to a guide device for positioning a sheet on the platen of the press.

In modern automatic job presses of the platen type, a sheet is automatically fed from a supply stack onto the platen, is automatically moved on the platen to the proper printing position, and is then imprinted by contact with the type bed by a combined swinging of the platen and the bed toward each other. The platens of these presses are covered by a tympan which normally is formed of paper and the sheet guides are mounted on the platen by cutting slots or openings in the paper tympan and securing them to the tympan or by sticking them into the tympan. It is a difficult and tedious job to properly locate these guides and when they are secured to the tympan they may be moved out of line by the vibration and jolting of the platen. Furthermore, this system is expensive, due to the fact that a new tympan is required for each job that is of a different size, and this is not only expensive from the standpoint of the cost of the tympan, but also from the standpoint of the time and labor it involves in removing and replacing the tympans and positioning the guides for the next job.

Having in mind the difficulties of the prior art apparatus it is an object of the invention to provide sheet guide means which may be adjustably mounted on a platen of a job press and employed universally for all sizes and types of jobs. It is another object of the invention to provide sheet guide means for platen presses that comprises simplicity of design, economy of construction and efficiency of operation.

The foregoing objects and others ancillary thereto are preferably accomplished, in accordance with the preferred embodiment of the invention, by a single guide member incorporating means for positioning sheets of any size that may be printed on a single platen and which may be adjustably mounted on the platen to accommodate sheets of different sizes without the need of change of the guides. This guide may be in the form of a bar having a plurality of sheet contacting members extending perpendicularly from one edge thereof and including aligned slots extending inwardly from the opposite edges of the bar. These slots are adapted to receive screws which may be permanently threaded in the face of the platen so that they need not be removed but may be employed for clamping the bar to the platen in adjusted position. By this arrangement, a tympan may be mounted on the

2

platens and holes punched through to accommodate the screws after which the tympan need not be changed until it is damaged from wear or other causes. The bar may be modified for 5 different types of presses and for one well-known type, may have a cut-away portion centrally of its leading edge to accommodate a pressure finger and its rear edge may be cut-away on one end to accommodate a side guide. For another type of 10 press, a side guide may be mounted on the bar itself so as to form a right angle with its front edge.

The novel features that are considered characteristic of the invention are set forth with particularity in the appended claim. The invention itself, however, both as to its organization and its method of operation, together with additional objects and advantages thereof, will best be understood from the following description of 15 specific embodiments when read in connection with the accompanying drawing, wherein like reference characters indicate like parts throughout and in which:

Fig. 1 is a view in perspective of a platen of 20 one type of press and having the sheet guide member of the present invention mounted thereon;

Fig. 2 is a cross-sectional view taken on a line 25 corresponding to line 2—2 of Fig. 1;

Fig. 3 is a top plan view of the guide member 30 incorporating a side guide; and

Fig. 4 is a fragmentary front view in elevation of the guide member and one of the sheet positioning devices thereof.

Referring now to the drawings, specifically to 35 Fig. 1, a platen 10 is shown as being of the type that is incorporated in the Kluge automatic job press which is one of the more popular presses now in use. The platen 10 has a tympan 11 mounted on its face and secured by a frame 12. 40 A side guide 13 is adjustably carried by a rod 14 adjacent the inner edge of the platen 10 and a sheet holder tongue 15 is supported by a rear frame 16. A plurality of suction fingers 17, are supported by a cross-bar 18 which is movably 45 carried by an arm 19, the suction fingers 17 being connected by tubes 20 with suitable source of suction.

The platen 10 is located between a stack 21 50 of paper and a type bed 22 and in the operation of the press a sheet of paper is transferred from the stack 21 to the platen 10, where it is picked up by the suction fingers 17 and moved forward by movement of the arm 19 to the front sheet 55 guides and simultaneously the side guide 13 is

moved laterally by movement of the rod 14 to contact and predeterminedly position the side edge of the sheet. The suction fingers 17 are then removed and the platen 10 swung upwardly while the type bed 22 is simultaneously swung forwardly to meet the platen and imprint the sheet thereon. The hereinbefore described press is well-known and consequently a description of the various elements for accomplishing the above described operation is not necessary in the present instance.

As previously stated the sheet to be imprinted is positioned on the platen 10 by the side guide and by front guides which are positioned on the tympan 11 in accordance with the size of the sheet to be printed. To determine the exact location of the guides it is customary to pull a print directly on the tympan 11 to locate the print relative to the platen 10. The measurement of the sheet is then figured around the print on the tympan and the tympan is then cut to permit the positioning of the front guides in accordance with this measurement.

To overcome the above difficulties, the present invention comprises a single guide member 25 that is in the form of a bar and has a plurality of sheet guides 26 projecting from its front edge 27 which is beveled, as best shown in Fig. 2, to permit passage of the suction fingers 17 in close proximity to the bar 25. Aligned slots 28 extend inwardly from both the front edge 27 and the rear edge 29 of the bar to receive the shanks of bolts 30 that are threaded into the platen 10. Obviously, these bolts 30 may be permanently positioned in the platen and merely loosened to permit adjustment of the bar 25 or they may be removable from the platen 10 to permit other uses of the platen 10 if desired. By this arrangement, the bar 25 may be adjusted through slots 28 while in a forward position, as shown in Fig. 1, to accommodate smaller sheets or it may be located in a rear position with the bolts 30 in the forward slots 28, whereby to accommodate larger sheets. It will be seen, therefore, that the single bar 25 may be employed for various sizes of sheets without affecting the position of the holding screws 30 or of the tympan 11. On the other hand the tympan 11 may be employed for many jobs and the only operation that is necessary in mounting it is to punch small apertures 31 to pass the bolts 30.

The guide member 25 is best shown in Fig. 3 wherein it may be seen that it comprises an elongated bar which is preferably provided with a V-shaped notch 32 in its front edge 27 to accommodate the forward end of the tongue 15, as shown in Fig. 2. The notch 32 is located centrally of the bar 25 and there are preferably four of the sheet guides 26 on one end of the bar whereas only two of the guides 26 are necessary on the other end of the bar, which latter end is the one adjoining the side guide 13. By this arrangement the necessary and proper sheet guides 26 are provided to accommodate all sizes of sheets ranging from the largest to the smallest that may be employed in the particular press. These sheet guides 26 are spaced not only in consideration of the sizes of the sheets with which they are to be employed, but also of the suction fingers 17 which must necessarily pass therebetween during the forward portion of their movement over the front edge 27 of the bar 25.

The guides 26 each comprise a pair of forwardly extending arms 33 which are spaced to receive a spring tongue 34 therebetween. The arms 33 are preferably formed integrally with bar 25 and have forwardly extending portions 35 that angle

upwardly and which terminate in downwardly extending vertical portions 36 which form abutments for the edge of the sheet. The bottoms of the vertical portions 36 are cut away to form reduced feet 37 which bear directly on the tympan 11. The spring tongue 34 is adjustably positioned at its rear end by a screw 38 that is threaded into the bar 25 in a position laterally of the spring 34 so that said spring may be adjusted longitudinally between the arms 33. The tongue 34 may be flat but preferably comprises an upwardly bowed portion 39 and a forward downwardly bowed portion 40 and terminates with the forwardly extending tip 41 which may turn up very slightly to guide the edge of the sheet downwardly against the vertical portions 36 of the arms 33.

In order to accommodate the side guide 13 the rear edge 29 of the bar 25 has a cut away portion 42 at the end adjacent said side guide 13. This cut away portion 42 comes into use only when the bar 25 is in its rear position as indicated in Fig. 1, by the broken lines R. In this position the rear edge 29 would normally interfere with the block 13' that is mounted on the rod 14. The cut away 42 however, fits around block 13' so as to accommodate the side guide 13 in any normal position as the bar 25 is placed in its rearward position only when larger sizes of sheets are to be printed and, consequently, the side guide 13 would necessarily be positioned toward the side of the platen to accommodate the larger sheets so that the cut away 42 extends along the rear edge 29 of the bar 25 for only a limited distance.

The guide member 25, hereinbefore described, is specifically adapted for a machine having a side guide 13 such as the aforementioned Kluge machines. Other well-known types of machines, however, do not incorporate the side guide 13 but employ small guides which are clipped to the tympan 11 or the platen 10 and are provided with positioning means that move the sheet angularly into contact with the front and the side guides. One of the better known machines of this type is the Craftsman press with a C and P automatic feeder. This type of press is provided with a finger in place of the tongue 15 which receives a pivotal or angular movement to move the sheet forwardly and laterally into contact with the front guides and the side guides. To cooperate with a machine of this type the guide bar 25 may be provided with an arm 43 that is positioned just outside of the mounting slots 28 at one end of the bar 25 and extends at right angles to the bar 25. The arm 43 has at least one sheet guide 44 mounted thereon to provide a side guide for the sheet and this guide may be fixed integrally with the arm such as the guides 26, or it may be formed independently and adjustably mounted to the arm 43 by means of a nut and bolt 45 and a slot 46 in the arm 43. Obviously more than one of the guides 44 may be employed if desired. The arm 43 may be formed integrally with the bar 25 or it may be formed independently to be removably attached to the bar 25 as by means of screws 47 which are adapted to cooperate with threaded apertures 48 in the bar 25. By providing an arm 43 as a removable attachment the guide member may then be adapted for use with either type of machine.

It will be obvious to those familiar with the art that the present invention provides many advantages over the present system. For instance, at the present time, it is the custom to pull a print on the tympan and then set the front or bottom guides and the side guides after laying out the size of the sheet around the print on the tympan.

A print is then pulled on a sheet and guides straightened if necessary.

In accordance with the present invention, however, the guide member is mounted on the platen by the screws 30 in its exact position in accordance with the size of the sheet and a print is pulled on a sheet rather than on the tympan. The important factor, however, is the fact that considerable time and labor is saved in setting up the single guide 25, instead of having to position and mount the plurality of individual guides.

Although a certain specific embodiment of the invention has been shown and described, it is obvious that many modifications thereof are possible.

That which I claim as new, is:

A sheet guide member for printing press platens having a pair of spaced screws thereon and for use with sheet moving means movable across and close to the platen for moving a sheet on the platen into position against the guide member, which member comprises an elongated bar having spaced pairs of transverse slots respectively in the front and rear edges of said bar for selective reception of the pair of screws on the platen, sheet guide elements spaced along and projecting from the front of said bar and each including a pair of spaced rigid arms with a spring finger therebetween, said arms extending in an upward incline from said bar and terminating in rigid downwardly bent vertical portions which extend to engagement with the

5 platen and form rigid abutments for the edge of a sheet, said spring finger being adjustably mounted on said bar and being bowed downwardly between said arms to substantially engage the platen between said vertical portions and curving upwardly beyond said vertical portions to guide and hold the edge of a sheet in abutment with said vertical portions, said bar having a beveled front edge between said sheet guide elements to provide clearance for the passage in close proximity thereto of the sheet moving means.

CECIL P. KUEVER.
